TIME DELAY FOR COMPRESSOR MOTOR CIRCUIT
Bruce M. Paul, Belleville, N.J., assignor to Worthington
Corporation, Harrison, N.J., a corporation of Delaware
Filed June 5, 1964, Ser. No. 372,929
3 Claims. (Cl. 62—153)

This invention relates to a motor control circuit, it relates in particular to a circuit for controlling operation of a motor compressor in a refrigeration system adapted to avoid unnecessary recycling of the compressor.

Recycling or a short cycling as used in the following description refers to a condition wherein the compressor motor, normally connected to a source of electrical current, is caused to restart frequently soon after stopping. Such repeated start-ups may be attributed to several effects. Primarily, the compressor motor is normally actuated in response to the load on the refrigeration system. For convenience, such control is associated with fluid flow from the system evaporator, as well as refrigerant flow in the system.

One condition found to cause recycling regardless of the loading condition on the system, occurs when excessive leakage of refrigerant gas to the system compressor provides a false load indication due to the build-up of gaseous refrigerant in the compressor. If such refrigerant leakage is excessive, the compressor will repeatedly recycle to pump down, and thereby cause undue wear and possible physical damage to the motor and its starting components.

Where the refrigeration system control includes other equipment such as pumps, fans, valves, etc., it is readily apparent that not only will the compressor be adversely effected by recycling, but the whole system is jeopardized.

To overcome excessive and repeated compressor recycling, the present invention provides time delay means in the control circuit for the system. Said control circuit embodies a timer device preset, and connected to the compressor current supply lines. Said control circuit includes a plurality of switches connected in parallel, and interposed in series with the compressor current supply, each of which switch is operated independently to complete the compressor motor circuit.

The invention relates particularly to a refrigeration system in which the motor is a component thereof to drive a hermetic compressor. Said motor is connected to the power source through the time delay device which is operable after each stoppage of the drive motor to prevent restarting within a predetermined time period. Also included in the circuit is means to by-pass the timer arrangement to permit a starting up of the refrigeration system when the need for cooling arises, regardless of the timing delay arrangement.

It is therefore an object of the invention to provide an improved compressor control circuit embodying means for preventing shortcycling of the compressor motor.

A further object of the invention is to provide an electrical circuit connected to a compressor motor and including time delay means interposed in the circuit for avoiding rapid recycling of the motor due to accumulation of refrigerant in the compressor.

Still another object of the invention is to provide in a refrigeration system having a motor driven compressor, a means for protecting said motor by avoiding rapid recycling caused by migrating refrigerant passing into the compressor during periods when the compressor is out of operation.

These and other objects of the invention will become clear to those skilled in the art from the following description made in conjunction with the accompanying drawing.

2

The single figure is a schematic drawing of the present control system shown embodied in a schematically illustrated refrigeration system.

Referring to the drawing, an embodiment of the control circuit is shown incorporated into a closed refrigeration system comprising well known refrigeration components. Compressor 10 may be of the centrifugal or the reciprocating type and includes a shaft extending therefrom and coupled to a drive motor 11. The latter is electrically connected to a source of current indicated as lines L1' and L2'.

Compressor 10 is communicated through line 12 to the inlet side of condenser 13, directing a stream of hot refrigerant gas to the latter. Condenser 13 may be exposed to the atmosphere, or provided with a fan 14 for passing ambient air or other heat transfer medium across refrigerant carrying coils. In the condenser, refrigerant is transformed to liquid phase and carried as liquid through conduits 17, receiver 15, and expansion means 16 to the inlet of evaporator 18.

In the expansion means 16, normally an expansion valve, expanded refrigerant is metered into heat exchange coils of evaporator 18, which are in heat exchange contact with a medium to be cooled. After being vaporized in evaporator 18, the gaseous refrigerant is passed in suction line 19 and thence redirected to the suction inlet of compressor 10.

The compressor motor in the system may be of the open or the hermetic type that is, enclosed completely in a single casing, without altering the function of the present control means. Referring to the electrical schematic section of the figure, the compressor motor is provided with a two line source of alternating current, L1', L2'. A line disconnect switch LDS is included in a manually operated starter having fuses F1 and F2 connected to protect the motor circuit from overloading.

Following standard practice, a motor switch MS which is represented in the circuit by an energizing coil, is protected from overheating by one or more current interrupting devices represented as switches SW1, SW2 and SW3, which are connected into the supply lines L1' or L2' and are exposed to the motor temperature. These switches may be actuated by a thermal element imbedded in the motor windings, or by a thermally resistive member positioned in the motor casing or as a part of overload relays, which might be incorporated into the system. Said switches control the current supply to the motor and function to hold the motor circuit open so long as motor overheating persists. In hermetic units of the type contemplated, cooling of internal components is usually achieved by passing low pressure refrigerant gas from the evaporator to the motor casing, prior to the introduction of said gas to the compressor. Thus the degree of cooling achieved at the motor is critical, consequently the use of suitable thermal protection is desirable.

Motor switch MS is connected electrically to current supply line L2, and through wire 23 to switch HLPSC which is responsive to a high-low pressure cutout relay actuated in accordance with the circuit refrigerant pressure. As shown in the figure, the HLPSC switch responds to pressure at condenser 13 upstream side, and at the evaporator downstream side, such that the pressure parameters of the refrigeration system might be maintained between predetermined values.

Pressure switch PS is connected through line 24 to series connected switches SW1, SW2, and SW3, thence to line L1. Pressure switch PS is actuated to open and closed position through sensing means responsive to the compressor pressure, and is the element that normally senses the presence of excessive refrigerant build-up downstream of the evaporator or in the low pressure suction side of compressor 10.

Protective relay coil 26 is connected to line L2, and in parallel to switches MS and HLPSCS. Protective relay coil PR includes an energizing coil activating two contacts PRS1 and PRS2. One side of coil 26 is connected through the normally open contact PRS1 to a terminal of pressure switch PS. The other contacts PRS2 are normally in the closed position and actuated to keep timer motor TM out of the circuit when coil 26 is energized. It is understood that TM may represent the timer motor coil, or merely an energizing coil controlling the timer motor circuit.

The switching sequence of contacts PRS1 and PRS2 is such that contacts PRS1 will close to make contact before contacts PRS2 breaks after being actuated by coil 26.

Contacts PRS1 is connected parallel to contacts TDS and SRS, each of which contacts is operable to connect motor switch MS to the current source as will be hereinafter explained.

A sustaining relay SR includes an energizing coil 27 connected through lines 28 to line L2. Coil LLS is connected to line L2 in parallel with energizing coil 27. Coil LLS functions to control the flow of refrigerant through valve 20 to initiate fluid flow through the refrigeration system as the compressor approaches operating conditions. A temperature responsive switch TS is connected in series with sustaining relay SR and with coil LLS. Actuating means associated with switch TS is in intimate contact with refrigerant leaving evaporator 18 to in effect sense the load imposed on the system. As the temperature in refrigeration line 19 decreases, indicating a decrease in load on the system, switch TS will open thereby de-energizing coil 27, and coil LLS.

The circuit timer device includes a timer motor TM operably connected through a suitable step-down gear train to a rotatable arm driven at a fraction of the shaft speed of TM. The slowly rotating arm is set to contact a normally open switch TDS, closing the circuit through motor switch MS.

It is understood that the timer motor TM presently shown, may assume a number of embodiments familiar to the art, and may be adapted to function within the circuit as will be hereinafter described.

Normally, and as presently shown, after the timer device has transversed a predetermined time cycle, the timer is automatically reset to a starting position in preparation for commencing another time cycle.

Suitable adjusting means may be built into the timer to permit delay of the compressor motor startup for any suitable time depending on the characteristics of the motor and the refrigeration circuit.

Operation

In the operation of the refrigeration system, startup of the compressor motor is initiated by closing switches LDS in the main disconnect switch. This disconnect as shown, includes a double pole single throw switch. It is appreciated however, that the disconnect may include the usual magnetic or electrically actuated relay having contacts of sufficiently large capacity to take the high starting current drawn from lines L1 and L2 by the motor switch MS.

It is assumed for the purpose of the present description that safety switches SW1 through SW3 respectively are closed, a condition indicating no damage or discontinuity in the windings of the motor field, starting and stator coils. If the temperature in the refrigeration system indicates a demand for cooling, temperature switch TS is closed. Thus, as current is supplied through lines L1-L2, temperature switch TS closes a circuit through line 33, switch TS and line 34. Current through energizing coil 27 closes contacts SRS. Energization of coil LLS adjusts valve 20 thereby permitting flow of liquid refrigerant from receiver 15 to expansion valve 16 and evaporator 18.

If the switch HLPSCS is closed, energization of coil 27, closes contacts SRS thereby completing the circuit from line L1 through switches SW1, SW2 and SW3 inclusive, switch PS, contacts SRS, switch HLPSCS, and motor switch MS to line L2. Closing of contacts SRS also completes a circuit through coil 26 which in turn opens contacts PRS2 and closes contacts PRS1.

With contacts PRS2 open, the timer motor TM is locked out of the circuit. Thus under normal running conditions, contacts PRS1, SRS are closed and contacts TDS is open.

As cooling load imposed on the refrigeration system is satisfied, and the temperature of the evaporator decreases, switch TS opens, thereby interrupting current flow through coil 27 of sustaining relay SR, and through coil LLS thereby interrupting flow of refrigerant to evaporator 18. Reduced refrigerant pressure at evaporator 18 causes switch PS to open thereby interrupting current flow to coil MS, and consequently stopping the compressor.

As coil 26 becomes de-energized, contacts PRS2 assume a normally closed position and apply current across the energizing windings of timer motor TM causing contacts TDS to revert to the normally open position. Thus contacts TDS, PRS1 and SRS are all open and TM has commenced a preset timed cycle.

If compressor crank case members, such as valves and glands, etc., develop a defect, there will be a consistent leakage of refrigerant into the crankcase or the low pressure chamber of the compressor thereby building up the pressure therein. Without the present control arrangement, such pressure build-up in the compressor will close switch PS thereby initiating operation of motor switches MS, to put the compressor into a pump down cycle. However, according to the objectives of the present invention, regardless of the pressure indication at switch PS even though the latter closes, contacts TDS, PRS1 and SRS maintain the motor switch MS open.

During the timed delay cycle, after a compressor motor stoppage when timer motor TM is energized, motor switch MS will be able to dissipate any heat accumulated during the operating period. Thereafter, at the lapse of the timed delay, switch PS may be closed due to increase in refrigerant pressure and at the end of the timed cycle, the actuating members of TM, functions to momentarily close contacts TDS, thereby momentarily completing the circuit through switch PS, contacts TDS, switch HLPSCS, to motor switch MS.

Assuming, switch PS to be closed, simultaneously, contacts TDS complete the circuit through switch PS, contacts TDS, line 36, coil 26, and line 29, to power line L2 to energize the coil. As the latter is energized contacts PRS1 are closed, and contacts PRS2 open in that sequence.

Closing of contacts PRS1 holds the motor switch MS closed even though contacts TDS remains open. Opening of contacts PRS2 interrupts the current flow to timer motor TM, which in turn opens contacts TDS after the momentary closing of the latter to initiate current flow into compressor motor 11.

Contacts PRS1 and PRS2 actuate in a make-before-break sequence to achieve two purposes. First, making of contacts PRS1, assures that the motor switch MS is energized through L1 and L2, to start up the compressor. Secondly, protecting relay PR coil 26 becomes energized to open contacts PRS2 thereby avoiding recycling of the timer motor TM through its complete delay period.

Motor switch MS will now continue to function for compressing refrigerant, and passage thereof through the refrigeration circuit until such time as the evaporator pressure is sufficiently reduced to open switch PS.

The present arrangement as mentioned, avoids rapid recycling of the compressor motor in response to a build-up in the compressor due to refrigerant leakage in the compressor. It further permits the time delay period to

be by-passed or to be shortened in the event the conditions at the system evaporator dictate a need for further cooling or starting up of the refrigeration system.

For example, during the delay cycle regardless of the position of switch PS, contacts TDS, PRS1 and SRS are opened, switch HLPSC is closed, contacts PRS2 are closed, and timer motor TM is energized.

A sudden demand for cooling will be signified by a closing of switch TS to complete the circuit through line 33, switch TS, line 34, coil 27 of the sustaining relay SR, and line 28 to line L2.

Energizing of coil 27 closes contacts SRS to complete the circuit through switch PS, and contacts SRS, line 36, coil 26 of protecting relay PR and coil 27. Energizing coil 27 further opens contacts PRS2 and interrupts the current flow to timer motor TM regardless of the time elapsed since the commencing of said timer cycle.

Thus, the disclosed control arrangement permits safe operation of a refrigeration system in such manner as to permit periodic pump down of the compressor to evacuate migrating refrigerant therefrom. It further protects the compressor motor system by avoiding the rapid recycling. The third feature incorporated into the instant arrangement is the characteristic of the circuit whereby the time delay period might be by-passed or interrupted to institute operation of the compressor to meet a load being imposed on the system at any time during the time delayed cycle.

It is understood that the present circuit represents a preferred embodiment of the invention and that certain modifications and changes may be made therein without departing from the spirit and scope of the invention.

What is claimed is:

1. A control circuit for refrigerant compressor motor forming a portion of closed system circulating a refrigerant, which system includes the compressor, a condenser, and an evaporator, said control circuit comprising:

(a) compressor motor switching means for connecting and disconnecting said compressor motor to and from a source of electrical power,

(b) temperature sensing means operative to measure the temperature of refrigerant and to energize said compressor motor switching means when the refrigerant temperature rises above a predetermined value to cause said compressor motor to be connected to the source of electrical power, said temperature sensing means being further operative to cause said compressor motor switching means to disconnect said

compressor motor from the source of electrical power when the temperature of the refrigerant drops below a predetermined value,

- (c) pressure sensing means operative to cause said compressor motor switching means to disconnect the compressor motor from the source of electrical power when the refrigerant pressure falls outside of a predetermined pressure range,
- (d) time delay means operative through said compressor motor switching means when said compressor motor is disconnected from the source of electrical power to initiate a time delay switching operation during which time delay period the compressor motor is maintained disconnected from the source of electrical power except for
- (e) said temperature sensing means being operative to connect the compressor motor to the source of electrical power whenever the temperature of the refrigerant in the system rises above the predetermined value.

2. The control circuit of claim 1 including

- (a) refrigerant flow control means, said refrigerant flow control means being operative to cutoff the flow of refrigerant in the system.
- (b) said temperature sensing means being further operative to cause said refrigerant flow control means to cutoff refrigerant flow in the system when the temperature in the system drops below the predetermined value.

3. The control circuit of claim 1 including:

- (a) compressor motor temperature sensing means operative to cause said compressor motor switching means to disconnect the compressor motor from the source of electrical power when the temperature of the compressor motor exceeds a predetermined value.
